(57) **CLAIM**

I claim the ornamental design for a LED cable with strain relief, as shown and described.

DESCRIPTION

FIG. 1 is a front perspective view of a LED cable with strain relief;

FIG. 2 is a top view of the LED cable with strain relief of FIG. 1;

FIG. 3 is a bottom view of the LED cable with strain relief of FIG. 1;

FIG. 4 is a front view of the LED cable with strain relief of FIG. 1;

FIG. 5 is a rear view of the LED cable with strain relief of FIG. 1;

FIG. 6 is a right view of the LED cable with strain relief of FIG. 1; and,

FIG. 7 is a left view of the LED cable with strain relief of FIG. 1.

The broken lines in the drawings are for the purpose of illustrating portions of the LED cable with strain relief that form no part of the claimed design.
